Attorney

UNITED STATES PATENT OFFICE.

JOHN A. ADELL AND ARTHUR H. STARRETT, OF ATHOL, MASSACHUSETTS, ASSIGNEES
TO THE L. S. STARRETT COMPANY, OF ATHOL, MASSACHUSETTS, A CORPORATION
OF MASSACHUSETTS.

HACK SAW.

Application filed February 3, 1921. Serial No. 442,230.

To all whom it may concern:

Be it known that we, JOHN A. ADELL and ARTHUR H. STARRETT, citizens of the United States, both residing at Athol, county of Worcester, and Commonwealth of Massachusetts, have invented certain new and useful Improvements in Hack Saws, of which the following is a specification.

This invention relates to hack saw frames, and particularly to such frames of extension type adapted to take blades of different lengths. In such devices it is desirable that the frame be so constructed as to render its manipulation easy, while maintaining simplicity of structure and freedom from projecting parts which might interfere with the manipulation of the saw or be fouled while it is in use.

Inasmuch as saw frames of this type usually provide for the tensioning of the blade, there has generally been a tendency upon the breaking of a blade or in the replacement of a worn blade of the frame to collapse or the parts thereof to be left adrift and dangle or turn, thus rendering the application of the new blade awkward and slow.

It is one object of the present invention, therefore, to provide a saw frame which while conforming in general to standard type will avoid the difficulties hereinbefore experienced. We accomplish these desired results first, by providing for control of the blade hangers so that they will retain position when not under tension; second, by providing a new structure in the frame for its adjustment; and third, by the general improvement in various details of mechanical refinement which add to the utility, adaptability and convenience of the tool.

In the accompanying drawings, we show a form of saw frame which not only well illustrates the principles of our invention, but is in itself found satisfactory in use and well adapted to the requirements of manufacture upon a commercial scale.

Throughout the specification and drawings like reference characters are correspondingly applied, and in the drawings:

Fig. I is an elevation of a sectional hack saw frame embodying the principles of our invention.

Fig. II is an enlarged detail of the coupling for the frame sections and particularly illustrating the self-locking construction of

the pawl for holding the adjustment of the frame sections.

Fig. III is a section on the line III—III of Fig. II.

Fig. IV is a detail section at the blade carrying end of the adjustable frame section. 60

Fig. V is a detail view of the blade clamping spindle shown in Fig. IV, removed.

Fig. VI is a side view of the thimble shown in Fig. IV, removed.

Fig. VII is an end view of such thimble. 65

Fig. VIII is a detail section at the blade carrying end of the handle section of the frame, and showing the blade clamping spindle at said end locked, and

Fig. IX is a similar view thereof and 70 showing said spindle released.

Our saw frame comprises a relatively stationary handle section 1 and an adjustable section 2. To the section 1 is fastened a tubular coupling 3 within which the free end 75 of the section 2 is adapted to be inserted and locked at selected positions of adjustment. The section 2 accordingly is provided along its upper face with a longitudinal series of notches 4 within which a locking pawl 5 80 pivoted between its ends at 6 in ears 7 formed on the coupling 3 is adapted to be selectively engaged. The pawl 5 is maintained normally engaged in a selected notch 4 by a coil spring 8 interposed between the 85 upper edge of the coupling 3 and the under face of the pawl heel. The spring 8 is overcome when the user applies his thumb to the heel of the pawl to rock the pawl on its pivot and withdraw the toe thereof from a 90 notch 4.

The coupling 3 is a tube having flat sides and rounded top and bottom edges. The top edge of said tube adjacent its forward end is notched as indicated at 8', Fig. II, 95 and beyond said notch is split and the portions thus separated turned outwardly into the planes of the side walls of the tube to provide the bearing ears 7 for the pawl 5 which lies between said ears and by them is 100 protected. The inner face of the pawl heel is beveled as indicated at 8", Fig. II, and the spring 8 is interposed between said bevel 8" and the bevel outer face of the notched portion 8'. This construction not only results in a neater finish, but permits the pawl 8 to be mounted closely adjacent the plane of the coupling 3, and so mounted the pawl

is protected against injury and against accidental disturbance of its setting.

The frame sections 1 and 2 when coupled as shown in Fig. I define a substantially U-shaped adjustable frame upon which blades B of varying sizes may be removably clamped. At its lower edge each frame section accordingly is provided with depending alined bearings 9 and 10 within which are rotatably mounted blade clamping hangers or spindles 11 and 12. Said spindles are each reduced at their opposing ends, as indicated at 13 to provide flat seats for the ends of the blade B and said seats have inclined pins 14 adapted to detachably engage in slots 15 at the blade ends.

The spindle 11 of the handle section 1 is circumferentially grooved between its ends, as indicated at 16, Fig. VIII, to receive a gravity detent 17, which is slidably mounted in a vertically disposed recess 18 formed in the lower edge of the handle section behind the bearing 9. Near its outer end said spindle is provided with a transverse pin 19 adapted to be selectively engaged in a circumferential series of notches 20 cut in the outer end of the bearing 9.

The spindle 12 of the adjustable frame section 2 beyond the flat seat portion 13 thereof is longitudinally grooved as indicated at 21, Figs. IV and V, and terminates in an outer threaded portion 22 which is similarly grooved as indicated at 23, groove 23 being a continuation of groove 21. The groove 21 is normally occupied by a blade spring 24 which is fast at one end to a thimble 25 applied to the outer threaded end of the spindle beyond the bearing 10. The free end of the spring is slightly outturned and when the blade B is clamped upon the said frame, said turned end lodges against the inner end of the bearing 10.

The inner end of the thimble is provided with one or more locking projections 26 adapted to seat in a circumferential series of notches 27 cut in the outer end of the bearing 10. Beyond the thimble a wing nut 28 is applied to the threaded portion 22 of the spindle. In assembling, the thimble 25 is applied to the outer end of the bearing 10, and the spindle 12 is inserted through the inner end of the bearing with its groove 21 receiving the spring 24. The nut 28 is then run onto the threaded end 22 of the spindle and set up against the thimble 25.

The spindle 11 is inserted through the bearing 9, the detent 17 initially moving upwardly into its recess 18 and subsequently dropping into the groove 16 to lock the spindle against longitudinal shifting movement in the bearing.

With the spindles thus assembled, and with the frame sections adjusted to space the spindles a distance apart approximately 65 the length of the blade to be attached, the

spindle 12 is adjusted longitudinally of its bearing 10 by means of the wing nut 28 until the pins 14 of the spindles will enter the slots 15 of the blade, and the blade is then strained to tension and clamped by continued rotation of the nut 28. Such action seats the pin 19 in the notches 20 of the bearing 9 and the projections 26 of the thimble 25 in the notches 27 of the bearing 10.

The blade is released by rotating the nut 28 in reverse direction to permit the blade to be disengaged from the pins 14. In such release, the detent 17 prevents the spindle 11 from shifting longitudinally in its bearing 9, and the spring 24 prevents accidental dropping out of the thimble 25 from the bearing 10 if the spindle 13 is removed, and also tends to keep the spindle 13 in place in the bearing if there is no saw blade to keep it under tension. It also tends to keep the spindle in its desired vertical position, although the thimble 25 can be withdrawn and reversed. The spindle 12 may be removed from its bearing only by backing off the nut 28, and then sliding the spindle inwardly towards the opposite spindle 11 thus disengaging from the spring 24. The spindle 11 may be removed from its bearing 9 by knocking out the pin 19 and sliding the spindle inwardly towards the opposite spindle 12, the detent 17 moving back into its recess in such withdrawal.

Various modifications in the form and construction of my device may obviously be resorted to if within the limits of the appended claims.

What we therefore claim and desire to secure by Letters Patent is:

1. In a saw, a frame having a spindle bearing, a blade clamping spindle adjustable in said bearing, a thimble mounted on said spindle beyond said bearing and movable into locking engagement therewith, means adjustable on said spindle beyond said thimble for holding said thimble in engagement with said bearing, and a blade spring disposed longitudinally of said spindle and fixed to said thimble at one end and engaging said bearing at its opposite end for maintaining the position of said spindle relative to said bearing when the thimble is disengaged from the bearing and the spindle released.

2. In a saw, a frame having a spindle bearing, a longitudinally grooved blade clamping spindle adjustable in said bearing, a thimble mounted on said spindle beyond said bearing and movable into locking engagement therewith, means adjustable on said spindle beyond said thimble for holding said thimble in engagement with said bearing, and a blade spring disposed in said groove and fixed to said thimble at one end and engaging said bearing at its opposite

end for maintaining the position of said spindle relative to said bearing when the thimble is disengaged from the bearing and the spindle released.

5 3. In a saw, a frame having a spindle bearing, a longitudinally grooved blade clamping spindle adjustable in said bearing and having a series of screw threads intersecting said groove, a thimble mounted on 10 said spindle beyond said bearing and movable into locking engagement therewith, a nut adjustable along said threads of the spindle beyond said thimble for holding said thimble in engagement with said bearing, 15 and a blade spring disposed in said groove and fixed to said thimble at one end and engaging said bearing at its opposite end for maintaining the position of said spindle relative to said bearing when the thimble is 20 disengaged from the bearing and the spindle released.

4. In a saw, a frame having a fixed bearing and having a recess opening into said bearing, a blade carrying spindle movable in 25 said bearing and having a circumferential groove between its ends, and a detent slid-

able in said recess and engageable in said groove to fix the position of the spindle in the bearing.

5. In a saw frame a spindle bearing, an 30 adjustable blade supporting spindle in said bearing, a thimble about said spindle and adjustably engageable therewith, and a resilient member detachably connecting said thimble with said bearing and frictionally 35 engaging said spindle to hold it against accidental dislodgment.

6. In a saw frame, a spindle bearing having an adjustable blade supporting spindle in said bearing, a thimble about said spindle 40 and a resilient key frictionally interengaging said spindle and thimble and detachably engaging said barrel to prevent accidental dislodgment of the parts in the absence of an assembled blade. 45

In testimony whereof we affix our signatures in presence of two witnesses.

JOHN A. ADELL.

ARTHUR H. STARRETT.
